Primary Examiner—Cathron C. Brooks

(74) *Attorney, Agent, or Firm*—William J. Daniel(57) **CLAIM**

The ornamental design for a chest, as shown and described.

DESCRIPTION

FIG. 1 is a front elevational view of a chest showing my new design;

FIG. 2 is a left side elevational view of the chest of FIG. 1; FIG. 3 is a right side elevational view of the chest of FIG. 1;

FIG. 4 is a top plan view thereof;

FIG. 5 is a greatly enlarged sectional view taken along line 5—5 of FIG. 1 showing in detail the cross-sectional configuration of a front corner portion of the chest;

FIG. 6 is a greatly enlarged sectional view taken along line 6—6 of FIG. 1 showing another portion of the claimed design;

FIG. 7 is a greatly enlarged sectional view taken along line 7—7 of FIG. 1 showing another portion of the claimed design; and,

FIG. 8 is a front elevational view of a second embodiment of the design of my invention, the views not shown are identical to those of the first embodiment except for the difference in height.

The drawer or door handles or pulls, shown in dotted lines, are for illustration purposes and do not form part of the claimed design.
